UNITED STATES PATENT OFFICE.

GEORGE B. GOODALL, OF SANFORD, MAINE.

PLUSH FABRIC.

SPECIFICATION forming part of Letters Patent No. 805,710, dated June 14, 1898.

Application filed October 15, 1897. Serial No. 655,271. (No specimens.)

To all whom it may concern:

Be it known that I, GEORGE B. GOODALL, of Sanford, county of York, State of Maine, have invented an Improvement in Plush Fabric, of which the following description, in connection with the accompanying drawings, is a specification, like letters on the drawings representing like parts.

This invention has for its object the production in a novel manner of a plush fabric or a pile fabric presenting a cut-pile face. By my novel method the face of the fabric may present at intervals, according to the design it is desired to produce, incut and uncut portions.

In accordance with my invention I first take a piece of looped-pile fabric woven in any usual manner and subject it to the action of size, which thoroughly permeates the pile and preferably also the back of the fabric, and when the size becomes dry the loops are stiffened, so that they will normally stand erect from the backing, and the loops are held securely in the backing by the size, so that when the standing sized and stiffened loops are being cut or sheared to make the plush the loops cannot be accidentally torn or pulled out to the detriment of the fabric. Then to produce a plush showing at its face a design or figure I have only to depress a portion of the sized, dried, and uncut pile-loops by the action of a suitable pattern-plate or die, and while so depressed I cut the stiffened standing pile and thereafter wash out or remove the size from the fabric, and, freed from size, the previously-depressed uncut pile-loops are raised and stand in the surrounding field of cut pile to present the desired design. The loops are cut while stiffened by the dried size yet on them, and thereafter the size will be washed out, leaving the pile soft, elastic, and pliable.

Figure 1 shows, in face view, a portion of a piece of pile fabric suitable for plush, the right-hand end of the pile face being represented as darker, it being supposed that that end has been sized. Fig. 2 is an edge view of Fig. 1. Fig. 3 shows a face view of a portion of the pile face of the fabric after the same has been sized and some of the uncut pile has been depressed. Fig. 4 is a central longitudinal section of Fig. 3. Fig. 5 is a view like that represented in Fig. 3, but with

the standing pile cut. Fig. 6 is a central longitudinal section of Fig. 5, and Fig. 7 an edge view showing part of the fabric Fig. 5 with the size removed to let the uncut pile rise in the field of the cut pile.

To make a plush fabric in accordance with my invention, I weave a pile fabric, it presenting a back *a* with a series of standing uncut loops *b*, the loops being composed of any usual or suitable material, such as commonly used in the manufacture of mohair, wool, or other plush. This pile fabric is then sized heavily, preferably on the face and back, the size permeating thoroughly the pile and back, so that when dried the pile and back are so stiffened that the pile may be cut and the pile-loops not be pulled out of the backing during the cutting operation. Then I take the sized and dried pile fabric and subject its pile-face to the action of a suitable embossing-pattern applied to the surface of a suitable roll or die having projecting surfaces corresponding in shape with the design to be produced and press the same firmly on the sized fabric, thus depressing or crushing down in figure or design, as at *c*, a portion of the sized pile-loops, leaving them depressed or crushed down below the level of the standing pile-loops, and thereafter the dried standing pile-loops may be cut by the action of a suitable rotary or other cutting-knife to leave cut loops *e* for the face of the plush. This pattern or roll may be more or less heated, as desired. After this the size may be washed from the fabric and the depressed or crushed-down uncut pile-loops *b* may then be raised, so that they will stand up, as in Fig. 7, and form part of the face of the fabric and show the figure or design.

The plush fabric containing patterns or figures as described will present a series of uncut pile-loops in a field of cut pile-loops, and the proportion of the uncut loops to the cut loops may vary accordingly to taste and the design to be produced.

The sizing of the pile-loops at the face is of great advantage, as it enables the embossing-pattern to act on a defined portion of the face of the fabric and form a clean-cut embossed figure, and the sizing of the back is also of material advantage, as the size cements the pile-loops and back together, so

that there is no danger of pulling out the loops during the cutting operation.

I am aware that it has been proposed in a British patent, No. 2,993 of 1860, to apply a slight stiffening to the back of a pile fabric, so as to hold in the loops, leaving this slight stiffening permanently in the fabric, it being so slight as not to affect the plush or loop side of the fabric; but my invention is quite distinct and radically different from this. I size the face of the fabric, and this sizing is heavy, so that the loops stand up stiff to be cut, and this sizing must be washed out, so as to give the desired soft effect. When washed out, the fabric has a soft, silky, and flexible cut-pile surface; but before washing it is rigid and harsh. The object of this feature of my invention is to give an absolutely even and smooth cut surface, the stiff piles standing evenly to be cut and not being capable of bending and becoming deflected from the cutting-knives.

Having described my invention, what I claim as new, and desire to secure by Letters Patent, is—

1. The herein-described method of producing plush fabric showing at its face a figure or design, which consists in sizing the uncut

pile-loops, drying said sized fabric, depressing or crushing down below the level of adjacent pile-loops, a portion of said dried, sized, uncut loops, thus leaving some of the sized and dried loops standing and stiff and others depressed; cutting the standing loops to form the plush face; and removing the size from the fabric which softens the same and permits the previously-depressed uncut loops of pile to rise and show uncut loops in a field of cut loops in design, substantially as described.

2. The herein-described method of producing plush fabric, which consists in heavily sizing the uncut pile-loops forming the face of the fabric; drying said heavily-sized pile-loops, rendering them stiff for standing against the cutting operation; cutting the loops to form the plush face; and removing the size, leaving the cut loops soft and pliable, substantially as described.

In testimony whereof I have signed my name to this specification in the presence of two subscribing witnesses.

GEO. B. GOODALL.
